UNITED STATES PATENT OFFICE.

JOHN W. STIEFEL, OF ST. PAUL, MINNESOTA.

RADIATOR FOR AUTOMOBILES.

1,283,950.

Specification of Letters Patent. Patented Nov. 5, 1918.

Application filed February 17, 1917. Serial No. 149,841.

To all whom it may concern:

Be it known that I, JOHN W. STIEFEL, a citizen of the United States, residing at St. Paul, in the county of Ramsey and State of Minnesota, have invented certain new and useful Improvements in Radiators for Automobiles, of which the following is a specification.

My invention relates to improvements in radiators for automobiles of the water circulating type, its object being to dispense with the water tubes forming part of the ordinary radiator, and to otherwise cheapen and simplify the construction and make the same more effective.

More particularly the invention consists in the construction, combination, and arrangement of parts hereinafter described and claimed.

20 In the accompanying drawings showing one embodiment of the invention,

Figure 1 is a perspective view of my improved radiator shown partly broken away.

Fig. 2 is a vertical section through the bottom portion of the radiator, showing it in inclined position assumed when the car is moving up an inclination, and

Fig. 3 is a detail view of the top part of one of the screens and an adjacent wall forming part of the radiator.

Referring to the accompanying drawings,

A represents the side walls of my improved radiator, the lower ends 2 of said walls being bent outwardly and secured as by rivets 3 to the automobile chassis 4. The front edges of the side walls are connected by a plurality of plates 5 spaced apart and directed downwardly relative to the radiator. The rear edges of the side walls A are similarly connected by a plurality of plates 6 spaced apart and directed upwardly relative to the radiator. Constituting the bottom of the radiator is a tank portion 7 connected by a tube 8 with the water circulating system. The radiator bottom 7 is formed with an oblique division wall 9 connecting the front and back of said bottom and being directed downwardly toward the rear. A wall 10 extends upwardly from the front end of the wall 9 to the top of the back wall of the radiator bottom. The walls 9 and

10 are formed with perforations 11 and 12 respectively for the purpose hereinafter pointed out. The front wall of the radiator bottom extends upwardly beyond the adjacent ends of the division walls 9 as shown best in Fig. 2.

A plurality of vertically disposed open-work partitions 13 are supported upon the wall 10. The partitions 13 are spaced apart as shown in Fig. 1 and extend upwardly between the plates 5 and 6 to the under side of the hollow radiator top 14. The bottom wall 15 of the radiator top is formed with openings 16 directly above the upper ends of the partitions 13. The upper ends 17 of the partitions 13 are preferably doubled upon themselves underneath the openings 16. The tubes 8 and 18 form opposite connections for the radiator with the water distributing system. The radiator top is formed with the usual filling inlet tube 19 to permit filling of the radiator.

In filling for use the water is poured through the inlet tube to supply the radiator in the ordinary way. The water when it is not being circulated stands at the bottom of the radiator below the open work or screen partitions and also below the wall 9 or approximately on the level with holes 11 as shown in Fig. 2. When water is being circulated as by the water pump ordinarily used it will pass from the tube 18 to the radiator top, thence passing through the openings 15 onto the screen partitions. The water will thence travel down the partitions and pass through openings 12 in the plate 10 onto the plate 9, and will then pass through opening 11 to the space below said plate 9. As the car carrying the radiator moves rapidly forward through space, the inertia in the water as it flows upon the plate 10 is not fully overcome, thereby causing a large portion of it to flow rearwardly. For the purpose of arresting a too rapid rearward flow of the water and thereby avoid splashing against the rear wall of the tank portion 7, the plate 10 is disposed in an approximately resultant angle with relation to the maximum speed at which the car may be safely driven, so that the water will be forced to flow up grade. This causes the water to

spread film-like over the plate 10, thereby delaying its descent and flow through the lower of the holes 12, thereby further cooling it. The upper holes 12 near the rear wall, 5 catch any water that may find its way to that uppermost portion of the plate 10, when the car is exceeding a normal rate of speed. The function of the lower plate 9 is identical with that of plate 10, except that it is operative in abrupt stops and backward driving 10 of the car. The turned or thickened upper ends 17 of the partitions assist in guiding the water as it passes from the openings 16 onto the body of the partitions. By having 15 the walls 9 and 10 inclined as above explained, the water from the partitions runs more freely into the hollow radiator bottom, and also the main body of water is forced back and forth through the holes 11 in said 20 wall 9 by the motion of the car.

The plates 5 being directed downwardly from the open front of the radiator to form deflector plates prevent water, etc., being blown into the interior of the radiator. The 25 plates 6 being directed upwardly at the open back of the radiator tend to direct any water that may be blown against them from the screen partitions back into the interior of the radiator, conserving the supply of 30 water.

The spaced walls 5 and 6, while having the advantages above noted, at the same time allow the circulation of air through the radiator to assist in the cooling action of the 35 water.

By my improved construction I avoid the objections of the ordinary tubular construction of radiator securing a construction which is particularly easy to keep from 40 leaking and very cheap and simple. My construction is particularly adapted for winter use as there is not the danger of freezing that there is in the ordinary tubular construction. In Fig. 2 the radiator is shown 45 tilted to a position with the car on an incline, showing how the water stays almost wholly below the top wall 10, the water having access to the space between the plates 9 and 10, solely through the holes 11, which 50 are at the lowermost edge of the plate 9. The car will travel over short steep grades, before the comparatively large body of water will have had time to flow through the holes 11, thereby controlling the water in 55 the tank to prevent obstruction of the spaces above wherein the cooled water is descending.

I claim:—

1. A radiator of the class described comprising side walls connected across the front and back by spaced inclined deflector plates, 60 said deflector plates 5 being inclined downwardly and plates 6 upwardly relative to the radiator and outwardly from said front and

back, a hollow radiator top supported by 65 said side walls, a hollow radiator bottom and a plurality of open-work vertically disposed partitions supported in spaced relationship above said bottom, and extending upwardly to said radiator top. 70

2. In combination an open front and back radiator, a hollow radiator bottom, a hollow radiator top, vertically disposed open-work partitions extending between said top and bottom and oppositely inclined deflector 75 plates extending away from and across the open front and back respectively of said radiator in spaced relationship.

3. A radiator of the class described comprising side walls connected front and back 80 by deflector plates arranged in spaced relationship, a hollow radiator top formed with bottom openings, a hollow radiator bottom having a rearwardly inclined top plate with openings therein and a plurality of vertically disposed open-work partitions extending between said radiator top and bottom in line with said openings. 85

4. A radiator of the class described comprising a hollow bottom, said bottom having 90 a rearwardly inclined top formed with openings, a radiator top supported above said bottom and formed with bottom openings, a plurality of vertically disposed open-work partitions extending in spaced relationship 95 from the openings in said radiator bottom to the openings in said radiator top.

5. A radiator of the class described comprising a hollow bottom, the top wall of said bottom being inclined upwardly and rearwardly, and obliquely disposed division wall extending downwardly and rearwardly from the front of said top wall, a radiator top supported above said radiator bottom and formed with bottom outlet openings and 100 a plurality of open-work partitions extending in spaced relationship from said radiator bottom to said radiator top in line with the outlet openings of said radiator top. 105

6. A radiator of the class described comprising a hollow bottom, the top wall of said bottom being inclined upwardly, and obliquely disposed division wall extending downwardly and rearwardly from the front of said top wall, a radiator top supported 110 above said radiator bottom and formed with bottom outlet openings, a plurality of open work partitions extending in spaced relationship from said radiator bottom to said radiator top in line with the outlet openings 115 of said radiator top and downwardly extending deflector plates arranged in spaced relationship across the front of said radiator. 120

7. A radiator of the class described comprising a hollow bottom, the top wall of said bottom being inclined upwardly, and obliquely disposed division wall extending downwardly and rearwardly from the front 125

of said top wall, a radiator top supported above said radiator bottom and formed with bottom outlet openings, a plurality of open work partitions extending in spaced relationship from said radiator bottom to said radiator top in line with the outlet openings of said radiator top, downwardly extending deflector plates arranged in spaced relationship across the front of said radiator, and up-

wardly directed deflector plates extending 10 in spaced relationship across the rear of said radiator.

In testimony whereof I affix my signature in presence of two witnesses.

JOHN W. STIEFEL.
